UNITED STATES PATENT OFFICE.

JOSEPH L. DONAT, OF CHICAGO, ILLINOIS.

TRAP-VALVE.

No. 873,518.

Specification of Letters Patent.

Patented Dec. 10, 1907.

Application filed December 6, 1906. Serial No. 346,532.

To all whom it may concern:

Be it known that I, JOSEPH L. DONAT, a citizen of the United States, residing at Chicago, in the county of Cook and State of Illinois, have invented certain new and useful Improvements in Trap-Valves, of which the following is a specification.

My invention relates to improvements in trap valves.

10 The object of my invention is to provide a device comprising a trap containing a valve, to be used in connection with certain fixtures such as basins, kitchen sinks, and the like, whereby the water from the trap may be conveniently drawn off to prevent damage that would otherwise result from freezing and whereby the opening communicating with the sewer may be effectually closed to prevent the entrance of sewer gas into the 20 premises.

Another object of my invention is to provide a valve, of the character described, whereby the drain conduit through which water is carried to the sewer may be closed, 25 as a result of which water may be retained in the sink, and such receptacle may be used in lieu of a laundry tub or dish washing basin, after which the valve may be turned to its normal position and the contained water 30 drained through the trap to the sewer.

These and other objects of my invention will become apparent to persons skilled in the art from the drawings and the following description.

35 In the drawings: Figure 1 is a central vertical section of my improved device applied to an ordinary kitchen sink, showing the valve turned to position for permitting free flow of water through the trap. Fig. 2 is a 40 similar view showing the valve turned to position completely closing the opening through the trap, thereby permitting water to be retained in the sink and closing the opening to the sewer against the inflow of 45 sewer gas. Fig. 3 is a plan view of the device. Fig. 4 is a section taken on line 4—4 of Fig. 2. Fig. 5 is a side elevation of the device.

In all of the views the same reference 50 characters indicate similar parts.

10 is a casing, preferably screw-threaded at its respective ends, as at 11 and 12. The central, vertically extending part 13 contains a rotatable valve 14. The valve 14 is 55 hollow and is preferably tapered to preserve

water-tight contact with the approximate side walls of the casing. Ports 14' and 14" are made through the walls of the valve to permit unobstructed flow of water through the trap 15 when the valve is turned into the 60 position shown in Fig. 1. When the valve is turned into the position shown in Fig. 2 the ports 14' and 14" are moved out of register with the conduit comprising part of the trap, and the solid side walls of the valve 65 close the said conduit on both sides of said valve.

Normally the trap 15 contains water, up to the line 15', to seal the conduit communicating with the sewer, against the introduction of sewer gas into the apartment in which the fixture is contained.

It is frequently desirable to empty the water from the trap 15 to prevent freezing, in which event the valve 14 is left in position 75 shown in Fig. 1, and the drip, or drain cock 16 is opened when the water in the trap 15, constituting the seal, will run out, after which the valve 14 may be turned into position shown in Fig. 2 to close the outlet to the 80 sewer to prevent the entrance of sewer gas.

In the illustrated embodiment a sink, such as 17, is connected to one end of the trap, as by pipe 18, the other end of the trap being connected to the drain by pipe 19. 85

The valve 14 is provided upon its upper surface with a flat perforated boss through which a double-headed rod, or handle 20 freely passes. After the valve has been turned, by this means, the rod may be 90 pushed back into its rearward position out of the way.

The washer 21 is perforated and threaded, and attaches to a threaded boss 22 made upon the lower end of the valve 14. The 95 boss is perforated and threaded, into which the drain valve 16 is inserted.

The trap is shown attached to pipes 18 and 19 by means of screw-threaded nuts 23 and 24. Any other means for this purpose, 100 however, such as wiped joints, may be employed.

Having thus described my invention, what I claim and desire to secure by Letters Patent, of the United States, is:

1. The combination, in a drain trap, of a U-shaped casing, having a drain opening at the bottom of the U, a valve in said bottom having a through passage and an opening 110 constantly effecting communication between

the drain opening and said through passage, and an independent valve controlling the drain opening.

2. As an article of manufacture, a drain trap structure comprising a casing providing downwardly extending legs connected at their lower ends, a valve in said connection controlling communication of the legs, said valve and the casing providing drain openings arranged in constant registration, and an independent valve controlling said drain openings.

3. The combination in a drain trap, of a U-shaped casing having a drain opening in its bottom, a valve rotatable on a vertical axis having a transverse through passage and a vertical passage from said transverse

passage through its bottom registering constantly with the drain opening in the casing, and another valve controlling said drain opening in the casing.

4. In a drain trap, a U-shaped casing, a valve, rotatable on a vertical axis positioned between the legs of the casing, with its top presented in like direction with the said legs, a boss upon the top of the valve, and a handle 20 passing freely through said boss.

In testimony whereof I hereunto set my hand in the presence of two witnesses.

JOSEPH L. DONAT.
